UNITED STATES PATENT OFFICE.

ULYSSES C. OBLOSSER, OF ROHRSBURG, PENNSYLVANIA, ASSIGNOR TO
SARAH M. OBLOSSER, OF SAME PLACE.

RAILWAY-SIGNAL.

SPECIFICATION forming part of Letters Patent No. 633,892, dated September 26, 1899.

Application filed April 24, 1899. Serial No. 714,389. (No model.)

To all whom it may concern:

Be it known that I, ULYSSES C. OBLOSSER, a citizen of the United States, residing at Rohrsburg, in the county of Columbia and State of Pennsylvania, have invented certain new and useful Improvements in Railway-Signals; and I do hereby declare the following to be a full, clear, and exact description of the invention, such as will enable others skilled in the art to 50 which it appertains to make and use the same.

This invention relates to signals for steam, electric, cable, and other propulsive railways, and is designed to give warning at a crossing or station of the approach of a car or train, 55 and thereby avoid collision or other accident.

While the invention is particularly designed for crossings, it may be used to advantage at any point along the length of a line of railway to give warning to following 60 trains that the preceding train is within the range of the section or block protected by the signal, thereby avoiding rear-end collision.

It will thus be seen that the invention is susceptible of use in a variety of positions, 65 and in adapting it to a particular use and situation it is apparent that many changes in the form, proportion, and minor details of construction may be resorted to without departing from the spirit or sacrificing any of 70 advantages of the invention.

The invention consists of the novel features, details of construction, and combinations of parts which hereinafter will be more particularly set forth, illustrated, and finally 75 noted in the subjoined claims.

In the drawings, Figure 1 is a perspective view of the signal as applied to a crossing. Fig. 2 is a plan view of the mechanism located at the crossing or station. Fig. 3 is a section on the line X X of Fig. 2, showing the 80 normal position of the parts. Fig. 4 is a view similar to Fig. 3, showing the relation of the co-operating elements when the signal is set to give warning of the approach of a car or train. Fig. 5 is a detail perspective view of the semaphore-arm. Fig. 6 is a detail view 85 in perspective of a trip by means of which the signal is set from the moving car or train.

Corresponding and like parts are referred 90 to in the following description and indicated

in all the views of the drawings by the same reference characters.

In the installation of the invention the operating parts are disposed at one side of the railway, as indicated most clearly in Fig. 1, 55 the railway being designated by the reference-numeral 1. The signaling devices are mounted upon the upper end of the post 2, set in a mortise at the end of tie a proper distance from the railway, and consist of a semaphore-arm 3 and a bracket 4 to receive a lamp 5 of any approved form or type. A hook 6 is applied to the bracket 4 and is intended to support an electric lamp when the latter is used. When the lamp is of the ordinary lantern-type, it is placed upon the bracket 4. 60

The semaphore-arm 3 is composed of companion members 7, spaced apart and extending in parallel relation, and is preferably constructed of a single strip of metal bent into 70 the form shown, the terminal portions of the strip being brought together and secured to the end of a toothed sector 8, which is mounted upon a pin or journal 9, projecting laterally from the post 2. A vertically-disposed bar 75 10 has its upper edge portion toothed for a short distance and in meshing relation with the teeth of the sector 8, said bar 10 and toothed sector being held in engagement by means of a plate or keeper 11, extending along 80 the outer sides of said parts and being secured at one end to a plate 12, applied to the post 2, and at its opposite end to the pin or journal 9, applied to and projecting outward 85 from said plate 12. The companion or parallel members 7 of the semaphore-arm are disposed so as to come upon opposite sides of the bracket 4 and are provided at their inner ends with openings 13, protected by colored glass, so as to indicate danger when the semaphore-arm is turned from a vertical into a horizontal position, the colored glasses registering with the lamp and projecting rays of 90 light of the same color as the glasses.

A base-plate 14, constituting a bed, is located adjacent to the foot of the post 2 and between the latter and the track and is provided with end bearings 15, in which are journaled transverse shafts 16 and 17 of like formation. Arms 18 are formed with or applied 95 100

to the ends of the transverse shafts adjacent to the post 2 and are connected by links 19 with the lower end of the vertical bar 10. Other arms 20 are applied to or formed with the ends of the transverse shafts facing the track and normally extend in a vertical direction, and their outer terminals are connected with trips 21, disposed at one side of the track and at some distance from the crossing or post 2. The arms 18 and 20 are disposed approximately at a right angle to each other, the arms 18 normally occupying a horizontal position and the outer arms 20 a vertical position. A cam 22 is secured to the outer end of the transverse shaft 17 and is formed with a shoulder 23, which is engaged by a detent 24 to hold the signal set after either one of the trips 21 has been actuated by the approaching car or train. The detent 24 is a short lever fulcrumed intermediate of its ends to a standard 25, rising vertically from the base-plate 14 and having a laterally-extending pin 26 at the end opposite the end coöperating with the cam 22.

25 A releasing-trip 27 is mounted in a bearing 28, applied to the bed 14, and has a cross-bar 29 applied to the inner end of its horizontal portion, slotted links 30 connecting the terminal portions of the cross-bar with the pin 26, whereby a depression of the upper end of the trip 27 in either direction will cause a lowering of the inner end of the detent and a disengagement of the outer end of the detent from the shoulder 23 of the cam. The longitudinal slots 31 of the links 30 receive the pin 26 and admit of said pin having play therein according to the direction of operation of the releasing-trip. A spring 32 is secured at one end to the standard 25, and its free end exerts a downward pressure upon the outer end of the detent 24 to hold it in engagement with the shoulder 23 of the cam when the signal is set.

The trips 21 are mounted in bearings 33, secured to the end portions of the rail-ties, and have pendent arms 34, bifurcated at their lower ends and receiving journaled blocks 35, through which pass the ends of the rods connecting the trips with the arms 20 of the transverse shafts 16 and 17. The connecting-rods 36 pass through suitable guides applied to the ties and have loose connection with the arms 34 and 20 and are returned to a normal position by springs 38, mounted thereon and confined between collars 39, adjustably secured to the rods 36 and the adjacent guides 37. Other coil-springs 40 are mounted upon the outer end portions of the connecting-rods 36 and are adapted to hold the trips 21 in position to be engaged by the striker or actuating device applied to the car or train for setting the signal. A resetting-spring 41 is mounted upon the inner end portion of one of the connecting-rods 36 and is confined between the adjacent arm 20 and the guide 37 nearest said arm. This spring 41 is of the coil type and expandible and is

compressed when the signal is set and normally tends to return the parts to a primal position when released.

When the coöperating parts of the signal have been assembled as shown in Fig. 1 and the track is clear, the semaphore-arm occupies a vertical position and at night the lamp shows a white light. On the approach of a car or train from either direction either one or the other of the trips 21 is actuated and causes an outward movement of the arms 20 and an upward movement of the free ends of the arms 18, thereby elevating the vertical bar 10 and causing the semaphore-arm to assume a horizontal position, so as to give warning of the approach of a car or train. In daylight the semaphore-arm can be readily seen, and at night the light of the lamp, viewed through the red glass applied to the members of the semaphore-arm, will indicate "danger." When the trip 21 is actuated, the cam 22 will turn with its shaft 17 and bring the shoulder 23 in position to be engaged by the detent 24, thereby holding the signal set until the pilot of the car or train reaches the crossing and strikes the releasing-trip 27 and disengages the detent 24 from the shoulder 23, when the resetting-spring 41, reacting, returns the parts to a normal position. When the moving car or train strikes the last trip 21 after passing the crossing or station, said trip is depressed without imparting any movement to the rod 36, coöperating therewith, since its pendent arm will move upon the rod against the tension of the spring 40, the latter returning the trip to a normal position when released from the striker or actuator applied to the car or train, as will be readily comprehended.

It is to be understood that the connecting-rods, the connections between them and the trips, and the actuating and the detent mechanisms are to be housed to protect them from rain, snow, ice, and dirt and from being tampered with. The housings are not shown, being omitted for the sake of clearness of illustration and because well understood.

Having thus described the invention, what is claimed as new is—

1. In a railway-signal of the type described, the combination with a bracket or support for a lamp, and a semaphore-arm comprising spaced members arranged to extend upon opposite sides of the said bracket or support, and provided with openings in transverse alignment and registering with the said lamp when the signal is set and having colored glass or the like applied to said openings, said spaced members being connected at their outer ends and having their inner terminal portions brought together and actuating mechanism for the semaphore-arm, as and for the purpose set forth.

2. In a railway-signal, the combination of a signal device, transverse shafts having arms disposed relatively at a right angle to each other, an operating-bar connected by links

with corresponding arms of the shafts, trips for setting the signal disposed along the length of the track remote from the signal and operatively connected with the other arms 5 of the said shafts, a detent mechanism for holding the signal when set, and a releasing-trip for freeing the signal from the detent mechanism, substantially as set forth.

3. In a railway-signal, the combination of 10 a signal device, an operating-bar therefor, spaced shafts provided with arms disposed approximately at a right angle to each other, links connecting corresponding arms of the 15 shafts with the operating-bar, trips operatively connected with the other arms of said shafts, a detent mechanism applied to one of the said shafts for holding the signal set, a releasing-trip having a cross-bar, and links connecting the terminal portions of said cross- 20 bar with the detent, as and for the purpose set forth.

4. In a signal mechanism, a signal device, a shaft operatively connected therewith, means for setting the signal, a detent for holding 25 the signal set, a releasing-trip comprising a cross-bar, and links connecting the terminal portions of the cross-bar with the said detent and having a limited and independent movement relative thereto, as and for the purpose 30 specified.

5. In a signal mechanism, a signal device, actuating mechanism therefor, a trip having a pendent arm vertically slotted, a block journaled in the slot, a connecting-rod passing through an opening of the journaled block 35 and a spring mounted upon the end portion of the connecting-rod adjacent to the trip and serving to maintain the latter in a normal position, substantially as described.

6. In a signal mechanism, the combination 40 of a signal device, spaced parallel shafts having terminal arms right-angularly disposed, an operating-bar, links connecting adjacent arms of the shafts with said bar, trips 45 remotely situated from the crossing or station and operatively connected with the other arms of the shafts, a resetting-spring, a shouldered cam secured to one of the said shafts, a spring-actuated detent to coöperate with the shouldered cam for holding the signal set, a releasing-trip 50 comprising a cross-bar, and slotted links connecting the terminal portions of said cross-bar with the detent, as and for the purpose set forth.

In testimony whereof I affix my signature 55 in presence of two witnesses.

ULYSSES C. OBLOSSER.
